US00D946920S

(12) **United States Design Patent** (10) Patent No.: **US D946,920 S**
(45) Date of Patent: **** Mar. 29, 2022**

(54) **CHAIR**

(71) Applicant: **Gubi**, Nordhavn (DK)

(72) Inventor: **Mathias Rasmussen**, Copenhagen N (DK)

(**) Term: **15 Years**

(21) Appl. No.: **35/511,404**

(22) Filed: **Jan. 29, 2021**

(80) **Hague Agreement Data**

Int. Filing Date: **Jan. 29, 2021**

Int. Reg. No.: **DM/212626**

Int. Reg. Date: **Jan. 29, 2021**

Int. Reg. Pub. Date: **Feb. 19, 2021**

(51) **LOC (13) Cl.** **06-01**

(52) **U.S. Cl.**

USPC **D6/369**; D6/370

(58) **Field of Classification Search**

USPC D6/334, 360, 361, 369, 370, 374, 376, D6/379, 380, 381

CPC .. A47C 1/00; A47C 1/14; A47C 1/143; A47C 4/00; A47C 1/027; A47C 1/08; A47C 5/00; A47C 7/00; A47C 7/02; A47C 7/16; A47C 7/18; A47C 7/24; A47C 7/36; A47C 7/40; A47C 7/50; A47C 7/54
